UNITED STATES PATENT OFFICE.

JAMES BARKER, OF ANN ARBOR, MICHIGAN.

INDEX ARRANGEMENT.

1,308,471.

Specification of Letters Patent.

Patented July 1, 1919.

Application filed May 4, 1918. Serial No. 232,426.

To all whom it may concern:

Be it known that I, JAMES BARKER, a citizen of the United States of America, residing at Ann Arbor, in the county of Washtenaw and State of Michigan, have invented certain new and useful Improvements in Index Arrangements, of which the following is a specification, reference being had thereto in the accompanying drawings.

10 This invention relates to an improved index arrangement and refers more particularly to an index arrangement of the type in which the name or other index data is covered by a celluloid or other guard member 15 which protects it in use.

Heretofore in the manufacture of folders, index cards and the like the index has been provided with a celluloid guard member which is permanently fastened over the name 20 or other index data. However such construction is so expensive as to prohibit the folder which is employed in ordinary use from being utilized as a transfer folder. This necessitates the employment of additional 25 transfer folders and also the additional work of transferring from one folder to the other.

The present invention contemplates a construction which can be economically manufactured and in which the celluloid, metal or other guard member is formed separate from the index card or folder and is attached thereto during the active use of the device and is so arranged as to be conveniently removed and applied to a new folder at the time 30 of transfer; to construct and arrange the parts that the index on the folder, card or other member which is protected by the removable guard or sheath when in active use 35 can also be retained when the folder is used for transfer purposes.

The invention also resides in the novel arrangement for preventing accidental displacement of the guard or sheath member 40 and in such further details of construction and arrangements and combinations of parts as will more fully hereinafter appear.

In the drawings:

Figure 1 is a perspective view of a folder 50 embodying my invention showing the sheath or guard partly removed;

Fig. 2 is a cross-section on the line 2—2 of Fig. 1, with the guard in position;

Fig. 3 is a perspective view showing a 55 slight modification.

Describing in detail the particular embodiment of my invention shown in the drawings, A designates a folder which comprises a sheath of Manila paper or other suitable material bent to form a back section B and 60 a front section C connected at the bottom by an integral return bend D. At its upper end the folder is provided with an index E, the particular construction and arrangement of which forms the salient feature of my invention. 65

In general the index comprises an inclined surface F which is preferably formed on an integral tab G which extends from the back section B upwardly then forwardly to produce the inclined surface F, downwardly and rearwardly to a position adjacent the front face of the back section B to which it is pasted or otherwise secured at H. In place 70 of forming this additional tab section of celluloid or metal permanently secured to the main body section of the folder the index slip J is positioned on top of the inclined surface F and when the device is in active use it is protected by a sheath K formed of celluloid or other suitable transparent material. 75

In the construction shown in Figs. 1 and 2 this sheath is formed with a back section L and inclined top-section L' and a forward flange L² arranged to fit over the V-shaped tab on the folder. The sheath is preferably arranged to have sufficient frictional contact with the tab so as to prevent its accidental displacement. However, in order to avoid 80 displacement of the sheath its back section L is preferably provided with a struck-out lug M which when it registers with the opening O in the tab section of the folder will spring into interlocking engagement therewith. This will lock the sheath from accidental 85 displacement so that the folder can be employed in active use the same as if the sheath were an integral part of the folder. 90

When, however, it is desired to transfer 100 the correspondence or other subject-matter at the beginning of the year or other period it is only necessary to insert a lead pencil or other member into the opening O and force the lug L back out of engagement so 105 that the sheath E can be slipped off from the tab section. The folder can then be transferred directly to the storage file without removing it from the cover formed by the sections B and C. By pasting or other- 110

wise securing the index strip J permanently to the inclined surface F of the tab section the transfer folder will be conveniently indexed. However, as the transfer folder is 5 seldom referred to it is not necessary to have it protected by a sheath or other guard. This allows the same set of sheaths or guards to be employed for different folders and the novel arrangement of the tab section further 10 permits the use of a single folder for active use and later for use as a transfer device.

In place of forming the sheath of celluloid or transparent material I may employ the construction shown in Fig. 3 in which 15 the sheath Q is made of metal and has an elongated aperture R through which the name or other data on the index tab is visible. The body portion of the metal guard is sufficient to protect the index tab in the 20 same manner that it is protected by the transparent sheath. Thus in both constructions there is an exterior member which can be taken hold of by the user when turning to any particular folder and in place of 25 grasping the index tab directly, the celluloid or metal sheath or guard is taken hold of. The tab is then protected both from becoming soiled or worn and as the same sheath or guard can be used over and over 30 again with different folders the ultimate cost is comparatively slight. In place of forming the tab G as an integral part of the back section it could of course be made as a separate member from Manila paper or

other suitable material and pasted to the 35 back section.

I therefore do not desire to limit my invention to the particular shape or form of sheath or guard shown and described and it is also obvious that in place of being employed on a folder it can be utilized with index cards and other devices of similar nature.

What I claim as my invention is:

1. The combination with a body section 45 having an index tab, of a removable sheath engaging said tab, said sheath having an inwardly extending resilient lug and said body section having an opening in which said lug engages.

2. The combination with a body section having an index tab member, of a removable sheath member engaging said tab member, one of said members having an inwardly extending resilient lug and the other having 55 an opening in which said lug engages.

3. The combination with a body section having an index tab downwardly return-bent and having its free edge secured to the surface of said body section, said return-bent portion having oppositely-inclined faces forming with the body section a triangular tube, of a sheath adapted to fit over 60 said return-bent portion and adapted to interlock therewith to prevent accidental displacement of said sheath from the tab.

In testimony whereof I affix my signature.
JAMES BARKER.
